UNITED STATES PATENT OFFICE.

HEINRICH GRUNEWALD, OF DISSEN, GERMANY.

AEROPLANE.

Application filed December 22, 1927, Serial No. 241,875, and in Germany May 3, 1927.

This invention relates to an improved aeroplane, of which the construction is based upon as true an imitation as possible of the flight of birds (aviation), the required driving power being thereby reduced to a minimum so that it is even possible to drive the aeroplane with the aid of the human muscular strength only.

The improved aeroplane is illustrated on 10 the accompanying drawings, in which:

Figs. 1 and 2 are respectively a plan view and a side view of the same,

Figs. 3, 3^a and 4 show diagrammatical representations of details of the wings there- 15 of,

Figs. 5 and 6 are respectively a fragmentary plan view and a side view of the tail thereof on a larger scale,

Figs. 7 to 10 inclusive show the driving 20 members for the movement of the wings on a larger scale in different sections and elevations,

Fig. 11 is a plan view of one feather of the wings, on a larger scale,

Figs. 12, 13 and 14 show some details in 25 perspective views,

Figs. 15, 16 and 17 show details of the skeleton for the wings, and

Figs. 18 and 19 are sections on the lines 30 XVIII—XVIII, and XIX—XIX respectively, of Fig. 15.

The frame 1 of the aeroplane carries two wings A and B and a tail C, which are pivotally connected thereto.

35 Each wing comprises a skeleton (Fig. 15) consisting of three bars 2, 3, 4 linked together by joints 5, 6. The axes of the latter are located at an angle to one another (Fig. 16), so that the bars 2, 3, 4, as soon as they 40 are folded, lie in different planes (see dotted-line position thereof in Fig. 17). Said bars are tightened with each other by means of parallelogram guides 7, 8. Said bars or 45 guides carry by means of bandages or the like, the rods 36 which are inserted in the feather quills of the wing feathers 10. Said feather quills are formed of curved metal sheets 29, 30 (Fig. 12), of which the lower one may again consist of two curved metal 50 sheets 30, 31 (Fig. 13) overlapping one another at 32. Thereby, an interlacing of the feather quills is created. Said metal sheets have flanges 33, between which thin elastic metal foils 34 of steel or light metal are 55 inserted with rubber tightenings and in common riveted to the curved metal sheets 29,

30, 31. Said metal foils 34 form the beards of the feather quills and can be of different length to suit the nature and kind of birds' feathers. For strengthening the same, they 60 are corrugated (Fig. 14) while they overlap each other like roof tiles. The corrugation of said metal foils does not extend to their outer edges, the foils remaining smooth in proximity thereof as shown at 35 (Fig. 14). 65 Thereby, a particular elasticity of the feather quill beards is attained. For, if at the up and down movement of the wings the air pressure acts upon the same, the feathers are closed with descending wing (Fig. 4, 70 downwardly pointing arrow) and opened or spread with ascending wing (Fig. 4, upwardly pointing arrow).

The feathers as afore described form the supporting planes of the wings A and B and 75 of the tail C. According to whether during the wing stroke the wing skeleton is more unfolded or more folded, the feathers are by the parallelogram guides 7, 8 alternately 80 more closed or more opened like a bird's wing. In order to attain during the wing stroke a troughlike formation of each wing (like that of a bird's wing), upon which the improved arrangement and its novel action are inter alia principally based, a separate 85 thumb wing 10^b (Figs. 1 and 15) is arranged at the front of each main wing, which thumb wing corresponds to the similar thumb wing of birds. Said thumb wing is adjustable, so that with ascending main wing it is adjusted 90 more to the plane of the latter (Fig. 3) while with descending main wing it is turned more transversely to the front edge of the latter (Fig. 3^a). With normal wing stroke, said adjustment of the thumb wing is 95 automatically effected by the holder 40, on which the feathers of the thumb wing 10^b are arranged, being turnable with a sleeve 41 (Fig. 15) about the outer bar 4 and influenced by a coil spring 42, while besides a 100 pulling cord 43 is attached to said holder and adapted to move in guides 44, 45 parallel to the bars 2, 3 and tightened to the frame 1 of the aeroplane. The parallelogram guide of the wing skeleton is thereby 105 supplemented. During the folding and unfolding of the wing skeleton, the thumb wing 10^b is automatically adjusted by the pulling cord 43, the holder 40 rebounding each time by action of the coil spring 42. To 110 increase the troughlike formation of each wing, the outer wing feathers 10^a are ar-

ranged on a separate holder 37 (Fig. 15) which is turnably mounted on the outer bar 4 and influenced by a coil spring 38 for a similar purpose to that of the holder 40 by the spring 42. Said holder 37 has an arm-like extension 39 which with a hook 47 engages with a certain play below the hook-shaped edge 46 (Fig. 19) of the holder 40. With an adjustment of the thumb wing holder 40, thus, the holder 37 of the outer wing feathers 10^a is automatically caused to participate in said adjustment. Said adjustments of the feathers 10^a and 10^b can furthermore take place intentionally for each individual wing for steering the aeroplane through curves or the like. To this end, each pulling cord 43 is further connected in the conventional manner with the steering lever 56 arranged in front of the aviator's seat 57 in the aeroplane.

The two wings A and B are set in striking motion by a driving mechanism of particular construction. As shown in Figs. 7 to 10, the same comprises a toothed or chain ring 19 that can be rotated, either, by a motor 26, of which the cooler 28 projects beyond the front end of the frame 1 of the aeroplane, and by means of a chain 27 (Fig. 2), or, by treadles (like bicycle pedals) operated by the muscular strength of the aviator's legs. Said ring 19 rolls then by means of rollers 20 on both faces thereof along annular races 18 of Z-shaped cross-section, which are arranged between ring sections 17 integral with the frame 1. Said ring 19 carries on both its faces a lug 21 attached at an angle thereto. Said lugs 21 contain ball-bearings 22, which are turnably arranged therein by means of Cardan joints 24 with rings 25 (Fig. 9), for the pins 23 of forked levers 11, which are joined to the wing skeleton. During the rotation of the toothed ring 19 each lever 11 oscillates with its bearing 15 about the frame 1 of the aeroplane. Besides, each lever 11 is with pins 16 thereon turnable in the plane about the bearing 15. Thereby, the wing stroke can become circulating during the up and down movement of the wings. For a correct adjustment of each wing, the bar 2 of its skeleton is adjustable in its respective lever 11 by means of a pivot 12 in the forked lever about which the bar 2 is turnable and by means of a series of holes 14 in the free end of said bar through either of which a locking bolt 13 passing through the lever 11 can be inserted (Figs. 7 and 10).

The feathers 10 of the tail C (Figs. 5 and 6) are with their rods 36 turnable about pins 50 in a support 48, springs 49 being interposed between all the inner ends of said rods 36, which are connected with a common pulling cord 52 passing through an orifice 51 in the support 48 and leading to the steering lever 56 mentioned. By pulling said cord

52, the tail feathers 10 are spread (see the dotted-line position of the outer feather 10^a in Fig. 5), while after release of the cord 52 the springs 49 act to return the tail feathers 10 to their original position.

The support 48 is pivoted at 53 to a rod 54, that is turnable in a bracket 55 of the frame 1 and that leads also to the steering lever 56. By turning the rod 54, the tail C can be turned to the right or the left, while besides it can be turned up and down, for height steering, into the dotted positions C^a and C^b shown in Fig. 2 about its pivot 53, which latter turning can be effected by suitable steering contrivances (not shown) known in the art.

The spaces between the feather rods 36 are, like in a bird's wing, covered by separate feathers 10^a, and the whole plumage of each wing can be adapted to that of the individual kinds of birds, such as an eagle, a buzzard, an albatross, or the like.

All parts of the aeroplane are, as far as possible, made of refined light metal, as are especially the wing and tail feathers, the weight of the aeroplane becoming thereby rather light, so that, for starting and landing the same, it is sufficient to provide a broad runner 58 with upwardly curved front end suspended from the underside of the frame 1 at the front part thereof by means of springs 60, while near the tail end of the aeroplane a rearwardly depending springy tongue 59 is arranged.

By the automatic adjustment of the wing feathers due to their parallelogramlike tightenings, of which the guides 7 are joined at 9 to the frame 1, and by the troughlike formation of the wings by means of the thumb wings 10^b and the outer wing feathers 10^a, it is attained that the air is effectively caught during the wing stroke while with ascending wing the air is allowed to freely pass therethrough due to the resiliency of the elastic wing feathers 10 and their beards 34 (Fig. 4). By the air pressure the elastic feather quills are tensioned in forward direction, so that at the subsequent untensioning of the wing feathers in rearward direction the aeroplane is driven forward.

What I claim, is:—

1. In an aeroplane, the combination with a frame thereof, an aviator's seat therein, a steering lever in front of said seat, two lateral striking wings and a tail pivotally connected to said frame, of a rotary gearing for operating said wings, a skeleton for each wing consisting of bars linked to each other at different angles, parallelogram guides for tightening said bars, adjustable wing feathers and a thumb wing on said skeleton, like the wing feathers and the thumb wing of birds, said thumb wing being turnable up and down during the wing stroke about the front edge of the wing and

the outer wing feathers participating in said turning movement thereby creating a troughlike formation of the wing during its stroke, and a pulling cord to intentionally 5 adjust said thumb wing and outer wing feathers also from said steering lever, said tail consisting of feathers like a bird's tail and being adjustable from the aviator's seat to the right and left and in up- and down- 10 ward directions while its feathers can be spread and closed.

2. An aeroplane as specified in claim 1, in which said rotary gearing for the wing motion comprises a toothed ring, annular 15 races guiding said ring between them, ring sections integral with said frame and supporting said annular races, lugs on both faces of said toothed ring projecting at an angle therefrom, ball-bearings in said lugs, 20 forked levers engaging with their pinlike ends in said ball-bearings and turnable and oscillatable about said frame, and holders on said levers carrying said wing skeletons.

3. An aeroplane as specified in claim 1, 25 in which said wing and tail feathers consist of curved metal sheets with lateral flanges forming the quills thereof, and of light elastic metal foils forming the feather beards on and riveted between said quills, said foils 30 being corrugated except for a smooth surface at their outer edges and overlapping each other like roof tiles.

4. An aeroplane as specified in claim 1, in which said wing and tail feathers consist 35 of curved metal sheets with lateral flanges forming the quills thereof, and of light elastic metal foils forming the feather beards on and riveted between said quills, said foils

being corrugated except for a smooth surface at their outer edges and overlapping each other like roof tiles, and said sheet metal quills consisting of several curved metal sheets having partly lateral flanges bearing upon each other and partly hooked edges engaging over each other. 40 45

5. In an aeroplane as specified in claim 1, in which said wing skeleton consists of three bars linked together by joints of which the axes lie at different angles of inclination, rods pivoted to said bars and guided by said parallelogram guides, said rods and bars holding the feather quills of the wing feathers. 50

6. In an aeroplane as specified in claim 1, holders turnable in dependence upon one 55 another on the outer bars of each wing skeleton for the thumb wing feathers and for the outer wing feathers, and coil springs influencing said holders and causing the same to rebound after the operation of said 60 thumb wing and said outer wing feathers, said holders being connected with said pulling cord.

7. In an aeroplane as specified in claim 1, a holder for the tail feathers of which the 65 quills are turnable therein and at their ends spring-influenced, and a common pulling cord attached to the ends of said quills and leading to said steering lever.

8. In an aeroplane as specified in claim 1, 70 a turnable rod leading to the aviator's seat and to which said tail is pivotally connected.

In testimony whereof I have hereunto set my hand.

HEINRICH GRUNEWALD.
